US00D554266S

(12) **United States Design Patent** (10) Patent No.: **US D554,266 S**
Striepe et al. (45) Date of Patent: **** Oct. 30, 2007**

(54) **PORTABLE DEVICE FOR MEASURING
HEART RATE**

(75) Inventors: **Harald Striepe**, Boulder Creek, CA
(US); **Alfredo Knecht**, Campbell, CA
(US)

(73) Assignee: **Quantum Intech, Inc.**, Boulder Creek,
CA (US)

(**) Term: **14 Years**

(21) Appl. No.: **29/261,376**

(22) Filed: **Jun. 13, 2006**

(51) LOC (8) Cl. **24-01**

(52) U.S. Cl. **D24/186**

(58) Field of Classification Search **D24/165,**
D24/167, 169, 186; D14/159; 600/508,
600/509, 511, 513, 515, 520, 523, 528; 128/668,
128/670, 710

See application file for complete search history.

(57) **CLAIM**

The ornamental design for a portable device for measuring heart rate, as shown and described.

DESCRIPTION

FIG. 1 is a top left perspective view from the left side of a portable device for measuring heart rate according to our novel design;

FIG. 2 is a top view thereof;

FIG. 3 is a top side view thereof;

FIG. 4 is a bottom side view thereof;

FIG. 5 is a right side view thereof, the left side view being mirror symmetrical; and,

FIG. 6 is a bottom view thereof.
